UNITED STATES PATENT OFFICE.

ABRAHAM NOVICK, OF NEW YORK, N. Y., ASSIGNOR, BY MESNE ASSIGNMENTS, TO UNITED STATES ENVELOPE COMPANY, OF SPRINGFIELD, MASSACHUSETTS, A CORPORATION OF MAINE.

FOLDING-MACHINE.

1,298,775.

Specification of Letters Patent. Patented Apr. 1, 1919.

Application filed May 31, 1917. Serial No. 171,872.

To all whom it may concern:

Be it known that I, ABRAHAM NOVICK, a citizen of the United States, and resident of the city of New York, in the county of 5 Kings and State of New York, have invented certain new and useful Improvements in Folding-Machines, of which the following is a specification.

This invention relates to that type of machines which fold a blank into a tapered open end envelop.

My improved mechanism is particularly adapted to the folding of the type of blank shown in Figure 3 in which triangular flaps 15 as 101 are left on the blank between the front flap and the side flaps for the purpose of providing a thickness of paper at the corners 104 of the finished envelop, which corner, in the ordinary type of envelop, is 20 unprotected.

My new machine folds the blank described into an envelop, means being provided whereby the triangular flaps 101 are prevented from dragging the side flaps with 25 them underneath the front flap when said front flap is folded.

One of the objects of this invention is the provision of simple and rapidly working means for folding a blank into an envelop 30 having tapered sides.

A further object of this invention is the provision of means for holding the corners of the blank between the front flap and the side flaps out of the way of the front flap 35 and away from the body of the blank until after the folding of said front flap is begun.

A still further object of this invention is the provision of means for urging a peculiarly shaped blank into accurate alinement for the purpose of creasing said blank, and the provision of means for simultaneously creasing the blank along two longitudinal lines oblique to the axis of the blank and 45 one line perpendicular to said axis.

To accomplish said objects, I employ the mechanisms shown in their preferred forms in the accompanying drawings, in which—

Fig. 1 is a plan view of my machine, various parts being broken away to show mechanism thereunder.

Fig. 2 is a vertical section on line 1—1 of Fig. 1, showing the creasing and folding mechanisms.

Fig. 3 is a plan view of the blank to be folded, showing the lines on which the

folds are to be made, and the means for alining said blank.

Fig. 4 is a plan view similar to Fig. 3 showing the blank creased and the corners 60 104 plaited and held down in readiness for the folding operations.

Fig. 5 is an elevation of Fig. 4 and Fig. 6 is a perspective drawing of the same.

Fig. 7 is a plan view of the blank and 65 front folder after the front fold has been completed, and Fig. 8 is a vertical section on line 7—7 of Fig. 7.

Fig. 9 is a plan view of the finished envelop and Fig. 10 is a section on line 9—9 70 of Fig. 9, the thickness of the paper being exaggerated for clearness.

Fig. 11 is a plan view of a portion of the plunger plate showing the spreader fingers attached thereto and Fig. 12 is a 75 vertical section on line 11—11 of Fig. 11.

Fig. 13 is an elevation showing the connections to the plunger rod for operating same.

The main table 1 is supported by side 80 frames 2, which frames carry main shaft 3. Driving pulley 4, obtaining power from a source not shown, is mounted on shaft 3 and rotates said shaft to actuate the various sub-mechanisms of my machine, said 85 sub-mechanisms being operatively connected to said shaft by suitable cams and connecting rods as 5 and 6 for imparting motion thereto in proper timed relation. Auxiliary table 7 is supported above table 1 by 90 posts as 8, and has mounted thereon the mechanism for urging the blank into alinement for creasing and the means for feeding the blank from an elevator table as 9 of the usual type to the upper end 17 of the creasing box 18.

The blank may be lifted from elevator table 9 by a picker 10 of the usual type whereby the blank is lifted from the stack by gumming ledges. Said picker 10 is supported for reciprocation by suitable mechanism in arch 11 mounted on table 1. Stripper plate 12 strips the blank from picker 10 on the upward reciprocation of said picker in the manner well known in the 105 art. The blank is then gripped between movable jaws 13 and stationary jaws 14 of the usual blank gripping operating mechanism 19 mounted on the reciprocating conveyors 15 running in grooves 16 in table 7. 110 The gripper operating mechanism 19 on its forward stroke strikes stop 20 on table

- 7 thereby bringing gripper jaws 13 and 14 together to grip the blank which has been brought up to stripping plate 12 by picker 10. Conveyer slides 15 are then moved rearwardly until the main portion of the blank is almost directly over creasing box end 17 when the gripper operating mechanisms strike cams 21 on table 7 opening jaws 13 and releasing the blank. Conveyer slides 10 15 are actuated by suitable mechanism connected to shaft 3, which mechanism can be designed by anyone skilled in the art to which this invention pertains, and which is not shown.
- 15 For engaging the marginal indents of flaps 101 and pushing the blank into accurate creasing position, alining pins 22 mounted on arms 23 and carrying blades 24 are used. Said blades 24 are adapted to engage 20 the straight edges of flaps 101 for straightening said blank into proper position, the blank being urged forward by the oscillation of pins 22, against rear stop 25 on table 7 and side stops 26 on the same table, 25 so that the edges of the blank on which the creases are to be made are directly over the inside faces of tapered creasing box 18 and directly under the corresponding edges of the tapered plunger plate 27. Arms 30 are attached to levers 28 and 128 pivoted at 29 on table 7, said levers being connected by the cross connecting rod 30 so that they will oscillate in opposite directions, (Fig. 1.) Lever 28 is oscillated through crank 31 on 35 shaft 32 supported in bearing 33 on table 1. Crank 34 on said shaft 32 is operated from main shaft 3 through a suitable cam as 5 and connecting rod as 6 passing through an opening 35 in table 1.
- 40 The blank is driven through the creasing box 18 by reciprocating plunger plate 27 attached to rod 36 and supported by plunger arch 37 supported on table 1. Said rod 36 is reciprocated through rock lever 38 connected to said rod and pivoted at 39 in lug 40 of arch 37, by connecting rod 41 operated through a suitable cam on main shaft 3, (Fig. 13.) Spreader fingers 42 are attached to the corners of the plate 27 at the narrow 45 end thereof, and are so shaped that they hold the corners of the blank away from the body thereof when said blank passes through the creasing box, openings 43 in table 7 being provided for said spreader fingers and blank corners to pass through.
- 50 The creasing box 18 is made up of the two vertical inside walls 44 oblique to the axis 106 of the blank 100 and vertical front wall 45 perpendicular to axis 106, the bottom of said box being the hinged trap 46. Stationary fingers 47 on table 1 are so shaped that they fit the notches in spreader fingers 42 and coöperate with said spreader fingers to form a plait 104 in the corners of the blank 55 between the front flap and the side flaps on the downward stroke of plunger plate 27, the last part of said stroke causing said plaited corners to be pushed under said fingers 47 by fingers 42, to be held there until after the folding of the front flap 102 is begun, (Figs. 4, 5 and 6.)
- 55 The folding of said front flap is accomplished by plate 48, cut away near the center to pass front wall 45 of the creasing box and mounted in shaft 49. Said shaft 49 is supported in bearings 50 and 51 and is operated by crank 52 through connecting rod 53 passing through opening 54 in table 1 and operated by a suitable cam on main shaft 3. The folding of the front flap 102 withdraws 60 the plaited corners 104 of the blank from under fingers 47 and lays the protecting flaps 101 against the upstanding side flaps 103, (Figs. 7 and 8.) The side flaps are folded down by means of folders 55 angularly disposed with regard to axis 106 of the blank, (Figs. 1 and 2) and pivoted in bearing 56 on table 1. Only one of said folders is shown, it being understood that this description applies also to another folder symmetrically placed in the machine. Said side folders are operated through levers 57 attached thereto, by means of bell crank levers 58 mounted on shafts 59 supported in bearings 60 on table 1, said bell crank levers being actuated by connecting rods 61 passing through opening 62 in table 1, by means of suitable cams on main shaft 3.
- 65 The operation of my improved machine is as follows:
- 70 Blank 100 is lifted from elevator table 9 by gummed picker 10 up to stripper plate 12, whereby the plate strips the blank from the picker. At the same instant, conveyer slides 15 are in their most forward position, 75 stops 20 closing movable jaws 13 and stationary jaws 14 of gripping mechanisms 19 together to cause them to grip the blank. Conveyer slides 15 are now moved rearwardly in grooves 16 whereby gripping mechanisms 19 are caused to release the blank at a point slightly in advance of creasing position by stationary cams 21.
- 75 Alining pins 22 are now oscillated toward each other to engage the marginal indents 80 of flaps 101 thereby urging the blank forward against stationary stop 25, blades 24 acting to straighten the blank against side stops 26 into accurate creasing position. Plunger plate 27 now descends and carries 85 the blank through creasing box 18 thereby causing the side flaps 103 and the front flap 102 to become partly folded and creasing the blank along two edges oblique to the axis 106 and one edge perpendicular to said axis, at 90 the same time that spreader fingers 42 hold part of flaps 101 away from the body of the blank. The last part of the downward motion of plate 27 presses the creased blank on to creasing box bottom 46 while spreader 95

5 fingers 42 coöperate with fingers 47 to plait part of flaps 101 and press the plaits formed underneath said fingers 47, whereby the plaits are temporarily held away from the body of the blank, said blank being left in the position shown in Figs. 4 and 5. Plunger plate 27 having been raised out of the way, front flap folder 48 is lowered by the rotation of shaft 49 carrying flap 102 down over the portion 10 of the blank which rests on bottom 46 and withdrawing the plaits from under fingers 47, at the same time creasing flaps 101 on a line continuous with the line on which the side flaps are creased. Side folders 55 15 are now operated to fold the gummed side flaps 103 on to front flap 102 thereby forming completed envelop 105.

As the blank is forced through the opening 17 in the table 7, Fig. 2, creases are 20 formed between the blank and the side flaps 103, and also between the blank 100 and the front flap 102, Fig. 3. The flaps 101 are forced through the openings 43 in the table 7 by the spreader fingers 42 and, therefore, are not creased. As the plunger 27 descends, the spreader fingers 42 force the flaps 101 outwardly, forming a fold or plait 104, Fig. 4, which is crowded past the fingers 47; said plait, by the resiliency of the 25 paper, springing beneath the stationary fingers 47, as represented in Fig. 4. As the front flap is folded by the folder 48, as represented in Fig. 7, the flaps 101 are drawn in against the side flaps 103, taking up the 30 plait which has been held under the fingers 47 and forming creases between the flaps 101 and 102. The triangular flaps 101 are prevented by the fingers 47 from forming plaits between the front flap 102 and the side flaps 35 40 103, and as the front flap is folded, the flaps 101 are drawn taut against the inner sides of the side flaps and interposed between them and the front flap 102.

What I claim is:

45 1. In an envelop folding machine of the class described, a creasing table, means for moving an envelop blank on said table and auxiliary means for continuing the movement of the blank on said table, comprising 50 a pair of studs journaled on each side of the path of the blank, arms carried by said studs and swinging in a plane parallel with the plane of the creasing table, pins carried by said arms engaging marginal indents in the 55 edges of the blank, and means for oscillating said studs in opposite directions.

2. The combination in a machine for folding an envelop blank having side flaps and a front flap with triangular flaps extending 60 from the side flaps upon each side of the front flap, of means for creasing the side flaps and front flap and forming a plait in said triangular flaps, and means for holding said plait until the front flap is folded.

65 3. In a machine for folding an envelop

blank having side flaps, a front flap and triangular flaps extending from said side flaps on each side of said front flap, means for folding the blank, comprising a table having an opening corresponding to the completed envelop, a plunger for forcing the blank through said opening, spreader fingers carried by said plunger and projecting over said triangular flaps, said table having openings for said fingers, and means for folding the front and side flaps of the blank. 70 75

4. In an envelop folding machine of the class described, a creasing table, means for squaring and positioning an envelop blank on said table, comprising stops, arms on each side of the blank, means for swinging said arms in opposite directions in a plane parallel with the creasing table, pins carried by said arms for engaging the marginal indents in the edges of the blank to move the blank 80 85 against said stops.

5. In an envelop folding machine of the class described, a creasing table, means for squaring and positioning an envelop blank on said table, comprising stops, arms on each side of the blank, pins carried by said arms, for engaging the marginal indents of the blank, blades carried by said arms for engaging the straight edges of the blank, and means for swinging said arms in a plane 90 95 parallel with the table and in opposite directions to move the blank against said stops.

6. In a machine for folding an envelop blank having side flaps, a front flap and triangular flaps extending from the side flaps on each side of the front flap and integral therewith, the combination of means for forming a plait in each of said triangular flaps prior to the final folding of the front flap, means for folding the flap, and means for folding the side flaps in the order named. 100 105

7. In a folding machine, the combination of means for feeding a blank, oscillatory alining pushers adapted for engaging the marginal indents of said blank and for urging said blank into alinement for creasing, means for creasing said blank, a reciprocating spreader finger adapted to engage and hold a corner of said blank away from the body of said blank, a stationary finger adapted to coöperate with said spreader finger for plaiting said corner, for receiving said plaited corner thereunder and for holding the plait away from the body of the blank until after the folding of the front flap is begun, means for folding the front flap whereby the plait is flattened against the side flap, and means for folding the side flap. 110 115 120 125

8. In a folding machine, a tapered reciprocating plunger plate, spreader fingers attached to and projecting from the corners of said plate at the narrow end thereof, a tapered creasing box having openings there- 130

- in for allowing said plunger plate and spreader fingers to pass through and stationary fingers adapted to coöperate with said spreader fingers for plaiting the corners 5 of a blank between the front flap and the side flaps for receiving said plaited corners thereunder and for holding the plait away from the body of said blank during further operation thereon.
10. 9. In a folding machine, means for feeding a blank, oscillatory alining pushers adapted for engaging the marginal indents in said blank and for urging said blank into alinement for creasing, a tapered reciprocating plunger plate, spreader fingers attached to and projecting from the corners of said plate at the narrow end thereof, a tapered creasing box having openings for allowing said plunger plate and said spreader fingers 15 to pass through, stationary fingers adapted to coöperate with said spreader fingers for plaiting the corners of a blank between the front flap and the side flaps, for receiving said plaited corners thereunder and for 20 holding the plait away from the body of said blank during further operation thereon, means for folding the front flap and means for folding the side flaps.
10. In a folding machine, means for feeding a blank, means for alining said blank, a tapered reciprocating plunger plate, spreader fingers attached to and projecting from the corners of said plate at the narrow end thereof, a tapered creasing box coöoperating 30 with said plunger plate for creasing said blank, said creasing box having openings therein for allowing said plunger plate and spreader fingers to pass through, stationary fingers adapted to coöperate with said spreader fingers for plaiting the corners of said blank between the front flap and the side flaps, for receiving the plaited corners 35 thereunder and for holding the plaits away from the body of the blank until after the front flap is folded, means for folding the front flap on said transverse crease whereby the plaits are straightened against the side 40 flaps and means for folding the side flaps on said longitudinal creases.
10. 11. In a folding machine, a tapered reciprocating plunger plate, a tapered creasing box for coöoperating with said plunger plate for making two longitudinal creases in a blank oblique to the axis of said blank and one transverse crease in said blank and 45 means for plaiting the corners of said blank between the front flap and the side flaps and for holding the plaits away from the body of said blank until after the folding of the front flap is begun.
10. 12. In a folding machine, a tapered reciprocating plunger plate, a tapered creasing box for coöoperating with said plunger plate for making two longitudinal creases in a blank oblique to the axis of said blank and one transverse crease in said blank, means 55 for plaiting the corners of said blank between the front flap and the side flaps and for holding the plaits away from the body of said blank until after the folding of the front flap is begun, means for folding the front flap on said transverse crease whereby the plaits are flattened against the side flaps and means for folding the side flaps on said longitudinal creases.
13. In a folding machine, means for feeding a blank, means for alining said blank, a tapered reciprocating plunger plate, spreader fingers attached to and projecting from the corners of said plate at the narrow end thereof, a tapered creasing box coöoperating 60 with said plunger plate for making two longitudinal creases in said blank oblique to the axis of said blank and one transverse crease in said blank, said creasing box having openings therein for allowing said plunger plate and spreader fingers to pass through, stationary fingers adapted to coöperate with said spreader fingers for plaiting the corners of said blank between the front flap and the side flaps, for receiving the plaited corners 65 thereunder and for holding the plaits away from the body of the blank until after the front flap is folded, means for folding the front flap on said transverse crease whereby the plaits are straightened against the side flaps and means for folding the side flaps on said longitudinal creases.
14. In a folding machine, the combination of means for feeding a blank, oscillatory alining pushers adapted for engaging the marginal indents in said blank and for urging said blank into alinement for creasing, a tapered reciprocating plunger plate, a tapered creasing box for coöoperating with said plunger plate for making two longitudinal creases in said blank oblique to the axis of said blank and one transverse crease in said blank, means for plaiting the corners of said blank between the front flap and the side flaps and for holding said plaits away 70 from the body of the blank until after the folding of the front flap is begun, means for folding the front flap on said transverse crease whereby the plaits are flattened against the side flaps and means for folding the side flaps on said longitudinal creases.
- Signed at the city of New York; in the county of New York, and State of New York, this 28th day of May, A. D. 1917.
- ABRAHAM NOVICK.
